UNITED STATES PATENT OFFICE.

HOWARD E. WATKINS, OF NEW YORK, N. Y., ASSIGNOR TO THE ENOS COMPANY, OF NEW YORK, N. Y., A CORPORATION OF NEW YORK.

DESIGN FOR A SHADE-HOLDER.

No. 39,592.

Specification for Design.

Patented Sept. 29, 1908.

Application filed May 13, 1908. Serial No. 432,742. Term of patent 14 years.

To all whom it may concern:

Be it known that I, HOWARD E. WATKINS, a citizen of the United States, residing at New York city, in the county of New York and State of New York, have invented a new, original, and ornamental Design for Shade-Holders, of which the following is a specification, reference being had to the accompanying drawing, forming a part thereof.

The figure is a side elevation of a shade holder, showing my new design.

I claim:

The ornamental design for a shade holder as shown.

HOWARD E. WATKINS.
